UNITED STATES PATENT OFFICE.

FREDERICK W. LETSCH, OF BALTIMORE, MARYLAND.

AUTOMATIC MATRIX-CLAMPING AND MOLD-ADJUSTING MECHANISM.

Application filed August 8, 1921. Serial No. 490,785.

To all whom it may concern:

Be it known that I, FREDERICK W. LETSCH, a citizen of the United States, and residing at Baltimore city, State of Maryland, have invented certain new and useful Improvements in Automatic Matrix-Clamping and Mold-Adjusting Mechanism, of which the following is a specification.

This invention relates to typographic machines and particularly machines for automatically clamping matrices in front of the mold cavity and varying the length of such cavity so that slugs or logotypes of any desired length may be cast. The invention involves certain improvements in the type of machine disclosed in my prior Patent, No. 1,381,205, dated June 14, 1921.

It is the object of the invention to provide improved mechanism by which the machine of my prior patent, particularly when used with the assembling and transfer mechanism of my co-pending application Serial No. 423,698 filed November 12, 1920, can be employed when desired for casting single types or logotypes containing any desired number of characters. A further object is to so arrange the improved mechanism that the machine may be employed to cast ordinary line matter by using matrices and justifying wedges in the usual manner and also employed without the use of justifying wedges to cast single types or logotypes containing varying numbers of characters, the simple manipulation of a latch or lock serving to

put the machine in condition to operate one way or the other as desired. A still further object is to provide yielding means for closing one end of the mold and for clamping the matrices during the casting operation thus making it unnecessary for the operator to give any attention to setting or adjusting of the mold cavity or the assembler when single types or logotypes of varying lengths are being cast.

My improved mechanism is of particular utility in connection with tabular work, where, for example, it is desired to print several columns of figures on a page, and where the number of figures in the various sums differ. The operation of setting up matter of that kind in the machines now in use is more or less unsatisfactory. Generally, the practice is to cast long slugs containing several groups of figures or characters and to saw or cut such slugs into proper lengths.

But this requires careful operation in cutting and trimming the slugs and when finally formed they contain transverse ribs, resulting from the casting in a closed mold, which ribs prevent proper locking up of the slugs in a straight line in the printing form. Where single type casting machines are employed in setting up such tabular matter, it is of course necessary to cast a separate type or slug for each figure or character, which requires that numerous slugs, each containing a single character, must be handled. With the machine of my prior patent having the present improvement applied thereto, ordinary line matter may be set up or by the simple manipulation of a latch or locking device, the machine may be put into condition to cast single types or logotypes of varying length without the necessity of manually varying the mold cavity so that the characters or figures making up the different sums of tabular work may be cast on separate slugs which may be easily assembled and handled and locked up in the printing forms.

The foregoing and other useful advantages are obtained by the construction described and illustrated in the accompanying drawings, forming part of this specification, it being apparent that numerous changes and modifications in the details of the constructions may be made without departing from the spirit of the invention or sacrificing any of its benefits.

In the accompanying drawings—

Figure 1 is a front view showing certain portions of a machine like that of my prior patent with the present improvements applied thereto.

Figure 2 is a view partly in section of the mechanism shown in Figure 1, this view being taken at right angles to Figure 1.

Figure 3 is a detailed view showing part of the mold and the means for closing the ends of the mold and clamping the matrices in position.

Figure 4 is a somewhat diagrammatic view showing the relation between certain parts of the machine embodied in my prior patent and the parts to which the present invention relates.

Many of the features hereinafter described and illustrated in the drawings are the same or substantially the same as corresponding features of my prior patent above

mentioned but brief reference to such features is necessary to a clear understanding of the present invention. The means for moving certain parts of the mechanism are not shown in the present drawings and it is to be understood that such means may be the same as employed in the patented machine.

Referring to the drawings in detail, 10 represents diagrammatically the means for 10 assembling and transferring matrices to the casting mechanism. This assembling and transfer mechanism is preferably of the type shown in my co-pending application above referred to, since with such mechanism, one 15 or more matrices may be placed in the assembler and supported while being carried to the casting mechanism. The numeral 11 represents generally the mechanism for receiving the assembled matrices and presenting 20 them to the mold during the casting operation and thereafter elevating the same in position to be carried to the distributor mechanism of the machine. The mold comprises an upper movable section 12 and a 25 lower stationary section 13, the left hand or delivery end of the mold being provided with an end gate 15, which carries an abutment 16 against which matrices are clamped during the casting operation. The end gate 30 serves to close the end of the mold while a cast is being made and suitable mechanism (not shown) is provided for moving the end gate into and out of operative position adjacent the mold. The other end of the mold 35 is closed by a body piece 17 which slides between the upper and lower sections of the mold, the upper mold section 12 during the casting operation being pressed against the body-piece by suitable mechanism (not 40 shown). Arranged in front of the body piece 17 is an end lock 18 which serves to contact with and support the matrices during the casting operation. The body piece 17 and end lock 18 really constitute a single 45 slidable member which is movable toward and from the end gate 15 in the manner hereinafter described. The end lock 18 is suitably connected to a sliding block 19 movable between the guides 20 and 50 21 secured to the frame of the machine. The end lock 18 is preferably provided with a tongue 22 which extends into a slot in the block 19 and is held therein by means of a set screw 23. The body piece 17 is also secured to the block 19 in any suitable manner. Preferably this block is provided with a lug 24 which engages a notch or opening in the body piece 17. At its right hand end 55 the block 19 carries a pin 25 which is adapted to contact with a cylindrical stepped gauge 26, this gauge being settable by the operator and forming the means by which the length of the mold cavity and consequently the length of the line is determined when ordinary line matter is being 60 65

cast. The sliding block 19 and the parts connected thereto are given a sliding movement through the medium of an arm 27, preferably made of two parts joined together and connected by a breakable pin 27^a 70 so that the upper portion of the arm will yield in case undue strain is placed thereon. The arm 27 is provided with a hub portion 28 which is rigidly secured by means of a pin 29 to a shaft 30 pivotally mounted in supports 31 of the machine. A downwardly extending arm 32 is also rigidly secured to the hub 28. The arms 27 and 32 thus constitute a lever which is pivotally mounted on the machine by means of the shaft 30. At its lower end the arm 32 carries a wheel 33 which is adapted to contact with a cam 34 mounted on the main cam shaft 35 of the machine. The wheel 33 is normally urged toward the cam 34 by means of a coiled spring 36 secured at one end to the frame of the machine and at the other end to an arm 37 also rigidly connected to the hub 28.

The cam 34 is substantially the same as that of my prior patent heretofore mentioned. It is provided with a high portion 34^a which extends part way around the circumference thereof, the rest of it being low. This cam together with the spring 36 cause the arm 27 and block 19 and the parts connected thereto to move through a certain cycle of operations. Briefly, this cycle of operations is as follows. When the high portion 34^a of the cam 34 is not operative 95 the arm 27 is caused to move to the right by action of the spring 36. This brings the pin 25 on the block 19 against the stepped gauge 26 which determines the length of the line to be cast, that is, it determines the position of the body-piece 17 and the length of the mold opening. After 100 the matrices have been positioned before the mold and locked up in the well known manner by means of justifying wedges and 105 after the slug has been cast and the matrices removed, the arm 27 due to the action of the high portion 34^a of cam 34 is caused to move toward the left and eject the cast slug from the mold, the end gate 15 in the meantime having been moved out of the way 110 by suitable mechanism.

The foregoing is the operation of the machine when ordinary line matter is being cast. When so operated it is necessary to 115 adjust the stepped gauge 26 in casting lines of different length, so that where the length of lines or slugs to be cast continually vary much attention from the operator is necessary. By the present improvements this 120 difficulty is avoided and the operation of the machine so modified that slugs of varying lengths may be cast without the necessity of adjusting the gauge 26 and the mold cavity. 125 130

The mechanism for accomplishing this improved result will now be described. Loosely mounted on the shaft 30 is a hub 40 which is provided with a downwardly extending arm 41 composed of two parts 41^a and 41^b between which a coiled spring 42 is mounted, this arrangement constituting a yielding arm for a purpose herein-after described. At its lower end the arm 10 carries a roller 43 which is adapted to bear on a cam 44 which is concentric with and arranged adjacent to the cam 34 here-fore described. Means are provided for locking the hub 40 to the shaft 30 when it 15 is desired to cast single type or short slugs without use of justifying means. The hub 40 is provided with a slot or recess 45 into which a lug or projection 46 is adapted to slide, this lug or projection being carried 20 on a slide or key 48 which slides longitudinally in a groove or way of the shaft 30. The hub 28 heretofore mentioned is also provided with a slot or recess adapted to receive the lug or projection 46. The 25 outer end of the key 48 is provided with a knurled head 49 by which the same may be operated and a small stop 50 is pivotally mounted on the head 49. This stop normally engages the end of the shaft 30 and 30 holds the lug 46 within the recess of the hub 28. The end of the shaft 30 adjacent the head 49 is provided with a recess 51 in which the stop 50 may be projected when the same is raised so that the key 48 may 35 be moved inwardly to engage the lug 46 with the slot 45 of the hub 40. From the foregoing it will be understood that when the lug 46 rests in the recess of the hub 28 the hub 40 will be disconnected from the 40 shaft 30 and the cam 44 will have no action on the movements of the arm 27. When, however, the lug or projection 46 is moved into the slot 45 of the hub 40 the latter is 45 locked to the shaft 30 so that the arm 27 and block 19 are moved under the influence of cam 44 as well as cam 34.

The cams 34 and 44 are so shaped that when both are operative, i. e., when the lug 46 rests in the slot 45, the action of cam 44 will modify the normal action of the cam 34. The cam 44 operates through the arms 27 and 41 which together constitute a yielding lever pivoted to the machine frame. The spring 42 of this lever is stronger than the spring 36 so that the latter will yield sooner than the former when motion is transmitted to the arm 27 from the cam 44. The cam 44 has a low surface indicated at 44^a a part of which is adjacent the low portion of cam 34. When both wheels 33, 43 rest on low parts of the cams the arm 27 together with the body piece 17 and end lock 18 will be drawn toward the right by the spring 36, the gage 26 being set, if 60 desired, to permit maximum movement of

such parts toward the right. When the parts have thus been moved toward the right, the matrices in any desired number may be presented to the mold. Assuming that the cam 44 is operative, it is apparent 70 that the spring 42 will exert a yielding action on the body-piece 17 and end lock 18 so that the matrices will be yieldingly clamped against the end gate by the pressure of this spring. Any desired number of matrices 75 may thus be positioned before the mold and be securely held by the pressure of the spring 42 while a case is made, although at such time the parts of the mold also tightly clamp the body piece 17. It will be understood that the surface 44^b of cam 44 is of such height as to cause the combined body piece and end lock 17, 18 to move toward the left a sufficient distance to clamp one or more matrices between it and the 80 abutment 16. On the other hand the low portions of cams 34 and 44 are such as to permit the member 17, 18 to be moved toward the right a distance sufficient to enable the maximum number of matrices to 85 be presented to the mold. Thus with the cam 44 operating, the member 17 and 18 reciprocates longitudinally of the mold cavity and the matrices presented to the mold, regardless of their number, will be 90 clamped and held during the casting operation and slugs of varying length may be made without changing any adjustment of the machine. No setting of the mold cavity is necessary and the slug produced will be 100 equal to the measure of the assembled line or matrix placed before the mold. After the casting operation is completed the high part 34^a of cam 34 comes into action and ejects the cast slug in the same manner 105 as when the cam 44 is inoperative. During this latter action it will be understood that the cam roller 43 will be lifted out of contact with the cam 44. When the slug is ejected the low part of cam 44 again comes 110 into play to position the arm 27 as here-fore stated.

It is apparent therefore that with the present improvements applied to the machine of my prior patent, particularly when employing the assembling and transfer mechanism of my co-pending application heretofore mentioned, such machine may be used to cast ordinary line matter and by the simple manipulation of the sliding lock 115 it may also be used to cast single types or logotypes of varying length without the necessity of manually changing the mold cavity or the assembler for different lengths of slugs.

Having thus described my invention what is claimed as new and desired to be secured by Letters Patent is:

1. In a typographic machine, a mold, means for positioning matrices adjacent the 120

1. mold, means for closing one end of the mold, means for closing the other end of the mold and for clamping the matrices during the casting operation, yieldable mechanism for moving said last named means toward the matrices, and means for further moving said last named means in the aforementioned direction to eject cast slugs from the mold.
2. In a typographic machine, a mold, means for positioning matrices adjacent the mold, a body-piece for closing one end of the mold during the casting operation, yieldable means for moving said body-piece toward the matrices after the same have been positioned before the mold, means for clamping the matrices during the casting operation, and means for further moving said body piece in the aforementioned direction to eject cast slugs from the mold.
3. In a typographic machine, a mold, means for positioning matrices adjacent the mold, a combined body-piece and end lock for closing one end of the mold and clamping the matrices during the casting operation, yieldable means for moving said body-piece and end lock toward the matrices to clamp the same, and means for further moving said body piece in the aforementioned direction to eject cast slugs from the mold.
4. In a typographic machine, mechanism for casting slugs of varying lengths, said mechanism comprising a mold having a slot, an abutment adjacent one end of said mold, a member for cooperating with said abutment to clamp matrices in front of said mold, yieldable means for causing said member to move from a position remote from said abutment to a position in close proximity thereto, whereby matrices presented to the mold regardless of their number will be clamped between said member and said abutment, means for varying the length of the mold slot to correspond with the number of clamped matrices, and means for presenting matrices to the mold.
5. In a typographic machine, a mold, means for positioning matrices adjacent the mold, an abutment against which the matrices are adapted to be clamped, a member movable toward said abutment to clamp the matrices against the abutment during the casting operation, yieldable means for moving said member toward said abutment, and means for further moving said member in the aforementioned direction to eject cast slugs from the mold.
6. In a typographic machine, a mold, means for positioning matrices adjacent the mold, an end gate for the mold, means for clamping the matrices against the end gate and closing one end of the mold during the casting operation, said means including a slidable member, yieldable means for moving said member toward the end gate, and means for further moving said member in the aforementioned direction to eject cast slugs from the mold.
7. In a typographic machine, mechanism for casting slugs of varying lengths, said mechanism comprising a mold having a slot, means for presenting matrices thereto, an abutment adjacent one end of the mold, a member movable toward and from said abutment, and yieldable means for moving said member to clamp the matrices between said abutment and said member regardless of the number of matrices presented to the mold and means for varying the length of the mold slot to correspond with the number of clamped matrices.
8. In a typographic machine, a mold, means for positioning matrices adjacent said mold, an end gate for the mold, an end lock movable toward and from the end gate, an arm for moving said end lock toward said end gate to clamp the matrices during the casting operation, a cam for moving said arm, a yieldable connection between said cam and arm whereby varying numbers of matrices may be clamped by said end-lock, and means for further moving said end lock in the aforementioned direction to eject cast slugs from the mold.
9. In a typographic machine, mechanism for casting slugs of varying lengths, a mold, an abutment adjacent one end of said mold, a member for cooperating with said abutment to clamp matrices in front of said mold, yieldable means for causing said member to move from a position remote of said abutment to a position in close proximity thereto, whereby matrices presented to the mold regardless of their number will be clamped between said member and said abutment, and means for further moving said member in the aforementioned direction to eject the cast slugs from the mold.
10. In a typographic machine, a mold, an abutment adjacent one end of the mold, a member for cooperating with said abutment to clamp matrices in front of the mold, yieldable means for moving said member toward said abutment from a position remote therefrom, whereby matrices presented to the mold will be clamped between said member and abutment during the casting operation, and means for further moving said member in the aforementioned direction to eject the cast slugs from the mold.
11. In a typographic machine, a mold, means for positioning matrices adjacent the mold, and means for clamping the matrices during the casting operation and ejecting the cast slugs from the mold, said last named means including a slidable member, a cam, a flexible lever connected to said member and

operated by said cam, and a second cam for moving said slideable member to eject cast slugs from the mold.

12. In a typographic machine, a mold, 5 means for positioning matrices adjacent the mold, and means for clamping the matrices during the casting operation and for ejecting the same from the mold, said last named means including an end-lock, an arm for 10 moving the end-lock, two cams for moving said arm, and yieldable means interposed between one of said cams and said arm.

13. In a typographic machine, a mold, 15 means for positioning matrices adjacent the mold and means for clamping the matrices during the casting operation, said last named means including, a slide, a flexible lever for moving said slide, said lever having two portions pivotally connected and a 20 coiled spring arranged between such portions, and means for moving said lever.

14. In a typographic machine, a mold, a movable arm pivotally secured to the machine, means movable by said arm for 25 clamping matrices adjacent the mold and closing one end of the mold during the casting operation, yieldable means for operating said arm in a direction to cause clamping of matrices positioned before the mold 30 and means for further moving said arm in the aforementioned direction to eject the cast slugs from the mold.

15. In a typographic machine, a mold, 35 a flexible lever pivotally mounted on the machine, a cam for moving said lever, means movable by said lever for clamping matrices adjacent the mold and closing one end of the mold during the casting operation, and a second cam operable on said last mentioned 40 means for ejecting the cast slugs from the mold.

16. In a typographic machine, a mold, means for closing one end of the mold, a 45 body-piece for closing the other end of the mold, a flexible lever for moving said body-piece toward said end closing means to close the mold, means for moving said lever, and means for moving said body-piece to eject the cast slug.

50 17. In a typographic machine, a mold, a body-piece for forming one end of the mold cavity, mechanism for operating said body-piece through a definite cycle of operations during the casting of one character of matter, mechanism for modifying the action of 55 said first named mechanism when casting matter of a different character, and a device for rendering said last named mechanism operative or inoperative at will.

60 18. In a typographic machine, a mold, a combined body-piece and end-lock for the mold, mechanism for moving said body-piece and end-lock through one cycle of operations when matter of one character is 65 being cast, mechanism for modifying the ac-

tion of said first named mechanism when matter of a different character is being cast, and a manually operated device for rendering said last named mechanism operative or inoperative at will.

70 19. In a typographic machine having a mold and means for positioning matrices adjacent the mold, the combination of a slideable member, means for moving said member and holding the same in a predetermined fixed position as matrices are positioned adjacent the mold and during the casting operation, alternative means for moving said slide toward the matrices and clamping the same after they have been positioned before the mold and during the casting operation, and a device for rendering the last named means operative or inoperative at will.

75 20. In a typographic machine, a mold, 80 means for assembling and positioning a line of matrices and space bands before the mold and justifying the same, an end-lock slidably mounted adjacent the mold for supporting the matrices during the casting operation, means for holding said end-lock in a predetermined fixed position as the assembled line of matrices and space bands is justified and during the casting operation, other means for moving said end-lock 85 against matrices and clamping the same during the casting operation when slugs of different length are to be cast, and a manually controlled device for rendering said last named means operative or inoperative 90 at will.

95 21. In a typographic machine, a mold, means for assembling and positioning matrices before the mold, a member movably mounted adjacent the mold, an adjustable 100 device for holding said member in a predetermined fixed position while a line of matrices is positioned for casting and during the casting operation, means for thereafter moving said member to eject the cast 105 slug, means for modifying the action of said first named means so as to cause said member to move against the matrices and yieldingly clamp the same during the casting operation 110 whereby slugs of different length may be 115 cast without adjustment of said adjustable device, and a manually controlled device for rendering said last named means operative or inoperative at will.

120 22. In a typographic machine, a mold, a slide movably mounted adjacent the mold, means for moving said slide, said means including a cam for causing said slide to move in a certain manner, a second cam for modifying the action of said first cam, and a device for rendering said second cam operative or inoperative at will.

125 23. In a typographic machine, an arm pivotally supported on the machine, a cam for moving said arm through a certain cycle 130

of operations, a second cam for modifying the action of the first cam, a device for rendering said second cam operative or inoperative at will, and means associated with 5 the casting mechanism of the machine to which said arm is connected.

24. In a typographic machine, a lever pivoted to the frame of the machine, means associated with the casting mechanism of 10 the machine connected to one end of the lever, a cam for moving the other end of the lever to cause the same to perform a certain cycle of operations, a second cam, means operated by said second cam for modifying the action of the first cam on said 15 lever, and a manually operated device for rendering said last named means operative or inoperative at will.

25. In a typographic machine, a lever pivoted to the frame of the machine, a cam for operating said lever through a certain cycle of operations when matter of one character is being cast, a second cam for operating on said lever and modifying the action 20 of said first cam when matter of another character is being cast, and a manually controlled device for rendering said last named cam operative or inoperative to move said lever.

26. In a typographic machine, a lever, a shaft pivotally supported on the machine to which said lever is rigidly secured intermediate its ends, a cam for engaging one arm of said lever to cause the other arm to 30 perform a certain cycle of operations when matter of one character is being cast, a

second cam, an arm pivotally supported on said shaft and engaging said last named cam, and a manually operated device for connecting said last named arm with said lever whereby operation of the first named cam on said lever is modified when matter of a different kind is being cast. 40

27. In a typographic machine, a shaft pivotally supported on the machine, an arm 45 rigidly secured to said shaft, a second arm normally loosely engaging said shaft, a cam for moving each of said arms, a third lever rigidly secured to said shaft and movable by one of said cams and said first arm through 50 a certain cycle of operations when matter of one kind is being cast, and a manually operated device for connecting said second arm to said shaft whereby the action of said last named cam is modified by the other 55 cam when matter of a different character is being cast.

28. In a typographic machine, two cams, two arms operated thereby, a third arm rigidly connected to one of said first named 60 arms and normally operated thereby through a certain cycle of operations while matter of one character is being cast, a manually operated device for connecting the other of said first named arms to said third arm whereby 65 the movements of said third arm are modified when matter of a different character is being cast.

In testimony whereof I hereunto affix my signature.

FREDERICK W. LETSCH.
